TOOTHERBRUSH HOLDER

Allen H. Amdur, Chicago, Ill.

Application October 24, 1933, Serial No. 695,014

3 Claims. (Cl. 132—84)

This invention relates to tooth brush holders, and its general object is to provide a holder that is capable of supporting one or more tooth brushes in a manner whereby they are protected against dirt, dust, and foreign matter, and while ready access may be had thereto in removing or replacing the same, they are retained in a clean and sanitary condition.

A further object of the invention is to provide a tooth brush holder that not only protects and supports one or more tooth brushes in row formation to facilitate a selection in removal for use, but means are provided for rendering the brushes antiseptic.

15 A further object of the invention is to provide a tooth brush holder in the form of a cabinet having ventilating means to produce circulation of air through the cabinet for the purpose of expediting drying of the brushes.

20 Another object of the invention is to provide a tooth brush holder that is capable of supporting a container of tooth cleansing material, such as a tube of tooth paste and the like, in a convenient manner for use.

25 A still further object of the invention is to provide a tooth brush holder in the form of a cabinet that is simple in construction, inexpensive to manufacture, and extremely efficient in use and service.

30 This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

40 Fig. 1 is a perspective view of the holder which forms the subject matter of the present invention;

Fig. 2 is a sectional view taken approximately on line 2—2 of Fig. 1, looking in the direction 45 of the arrows;

Fig. 3 is a sectional view taken approximately on line 3—3 of Fig. 2, looking in the direction of the arrows;

Fig. 4 is a sectional view taken approximately on line 4—4 in Fig. 3, looking in the direction of the arrows; and

Fig. 5 is a perspective view of a modified form of my holder.

Referring to the drawing in detail, and particularly to Figs. 1 to 4, inclusive, it will be

5 noted that my holder which is in the form of a cabinet includes end walls 1, a top wall 2; a rear wall 3; a bottom wall 4; and a front wall 5, the latter extending downwardly from the top wall for a portion of the front of the cabinet and having an elongated opening therein which takes up the major portion of the front wall, as clearly shown in Fig. 1. The opening is closed by a sliding door 6 that extends through a slot in one end wall and is received and guided in grooves 7, as shown in Fig. 2. Disposed adjacent the inner end of the sliding door 6 is a recess providing a finger hold to facilitate the sliding movement of the door, as will be apparent.

10 The remaining portion of the front of the cabinet is open, but this open portion is closed by a door 8 that has formed on or otherwise secured thereto hinge barrels 9 co-operating with like hinge barrels 10 on the front wall 5, to receive pins 11 for hingedly securing the door 8 15 to the front wall, and this door when in closed position rests against the front edges of the bottom and end walls in tight association therewith, due to gravity. A knob is secured to the door 8 whereby it can be readily opened.

20 The bottom wall 4, as shown, is disposed slightly above the lower edges of the rear and end walls and at regular intervals in its length are arranged keyhole-shaped slots 12 having their narrow portions extending from the front edge 25 thereof for the purpose of receiving tooth brushes, and guiding them to the rounded portions which are beveled to provide a seat for the bristles of the brushes, as indicated in dotted lines in Figs. 2 and 4, with the result the bristles will be 30 wholly confined within the cabinet while the handles depend therefrom so that a quick selection can be made prior to opening the door 8, which when in open position any one or all of the brushes can be readily removed and replaced.

35 Disposed in the cabinet in the form as shown in Figs. 1 to 4, inclusive, is a partition 13 having an opening extending for the major portion of its length and width that is covered by a strip 14 of screen wire or the like, to provide in the cabinet a chamber to receive antiseptic material, not shown, whereby the fumes from the antiseptic material will pass through the interstices of the strip and come in contact with the bristles of the brushes. It will be apparent that the strip 40 45 14 can support an absorbent material saturated with antiseptic solution or the like.

45 In the form as shown in Fig. 5 the antiseptic chamber is eliminated, but this form is otherwise similar to the form shown in Figs. 1 to 4, 50 55

inclusive, and the top wall, which for distinction is indicated by the reference numeral 15, like the top wall 2 is curved in concaved formation to provide a pocket to receive a container of tooth 5 cleansing material such as a tube of tooth paste, as shown in dotted lines in Figs. 1 and 2.

The end walls in both forms of the invention as shown are each provided with ventilating means in the form of slots having hoods 17 disposed in 10 the front thereof, to retard the passage of dust and the like into the cabinet but allows for the free passage of air therein with the result the air will circulate throughout the interior of the cabinet and expedite drying of the brushes.

15 Both forms of the invention have arranged in the rear walls thereof keyhole-shaped slots 16 for the purpose of receiving securing means such as 20 nails, screws, and the like, for suitably supporting the cabinet in position for use.

20 While I have shown the cabinet as having its walls and partition integral, I want it understood that they can be secured together in any manner, and the cabinet can be made from any material and of course in various colors and shades thereof.

25 From the above description and disclosure of the drawing it will be obvious that I have provided a tooth brush holder in the form of a cabinet that not only protects and retains tooth brushes in a clean and sanitary condition, but 30 the brushes as well as the cabinet are rendered free from bacteria due to the antiseptic chamber in the form as shown in Figs. 1 to 4, inclusive, and in both forms the brushes may be easily and expeditiously removed and replaced due to the 35 slotted bottom walls, and the swinging hinged doors.

It is though from the foregoing description that the advantages and novel features of my invention will be readily apparent.

40 I desire it to be understood that I may make changes in the construction and in the combination and arrangement of the several parts, provided that such changes fall within the scope of the appended claims.

I claim:

1. A toothbrush cabinet comprising a body having a solid flat vertical back, sides therefor, each side having at least one ventilating louvre in the bottom portion thereof only, a concave top 5 co-operating with the sides to form a smooth concave surface having its longest dimension parallel to the back, said sides and top meeting within the concave surface, a perforated shelf extending between the upper solid portions of the two sides, 10 a door accessible from the outside closing the front of the compartment formed between said top and shelf, an additional shelf adjacent the bottom of said cabinet and being provided with a plurality of slots therein for receiving tooth 15 brushes, and a door horizontally hinged at the top of said lower tooth brush compartment and adapted to close said lower compartment and maintain said brushes in position.

2. The structure of claim 1 wherein said upper 20 door is adapted to slide horizontally.

3. A tooth brush cabinet, comprising a body having a solid flat vertical back, sides therefor extending the full width of the back, each side having at least one ventilating louvre in the bottom portion thereof only, a concave top co-operating with the sides and back to form a smooth concave surface having its longest dimension parallel to the back, a rim extending down from the top and extending from the edges of the top portions of the two sides, a perforated shelf beneath the top and extending across from the sides to form a top compartment in said cabinet, access to which is obtained by said front rim, a door mounted behind said rim and slideable 35 through a slot in one of said side portions, a bottom shelf extending across said cabinet at the lower portion thereof and being provided with a plurality of slots for receiving tooth brushes, said slots having their open ends along the front edge 40 of said shelf, and a door horizontally hinged on the lower portion of said rim, said door being large enough to close said lower compartment.

ALLEN H. AMDUR.
